UNITED STATES PATENT OFFICE.

MOSES E. LEWIS, OF TOLAR, TEXAS.

INCUBATOR.

Application filed August 24, 1923. Serial No. 659,218.

To all whom it may concern:

Be it known that I, MOSES E. LEWIS, a citizen of the United States, residing at Tolar, in the county of Hood and State of

5 Texas, have invented new and useful Improvements in Incubators, of which the following is a specification.

This invention relates to incubators and contemplates a strong and simple construction, with a novel construction of means for regulating the temperature of the incubator.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a front elevation of the incubator.

25 Figure 2 is a view taken at a right angle to Figure 1 with the door open showing the tray partly removed.

Figure 3 is a top plan view.

30 Figure 4 is a sectional view taken on the line 4—4 of Figure 2, showing the normal position of the heat regulator.

Figure 5 is a similar view showing the active position thereof.

Figure 6 is a detail view of the radiator.

35 Referring to the drawings in detail, 10 indicates the body of the incubator which of course can be constructed from any suitable material, and vary in size and configuration without departing from the spirit

40 of the invention. The body is preferably of rectangular formation in plan, and the bottom is provided with a plurality of air inlet openings 11. One side of the body is provided with a door opening, normally closed

45 by a hinged door 12, and this of course permits access to be had to the incubator, and also allows the tray 13 to be conveniently inserted and removed from the body portion when desired. The door of course is

50 held closed by any suitable means and is further provided with a sight opening 14, although all the walls may be provided with such openings if desired which openings are covered by suitable transparent

55 material. The tray slides upon and is supported by cleats which are secured to the

opposite walls of the body 10 thereby spacing the tray a slight distance from the bottom of the incubator.

The incubator is heated by a heater 18 60 which may be of any suitable construction, the heater being preferably in the form of a lamp as shown which is supported upon a platform or base 19 secured to one end of a bracket 20 which in turn is suspended from 65 one side wall of the incubator. Arranged immediately above this heater and supported by the adjacent side wall of the incubator is a casing 21 having an opening in the bottom thereof, indicated at 22 to receive the 70 heat from the heater as is obvious. This casing 21 is slotted as at 23 and this slot coincides with a slot 24 formed in the adjacent side wall of the incubator to receive the neck portion 25 of a radiator 26. This 75 radiator is of a size and shape to snugly accommodate itself within the body of the incubator and is supported immediately above the tray above mentioned. The neck portion 25 communicates with a water container 27 which container surrounds a chimney 28 through which the products of combustion pass as they enter the opening 22 in the bottom of the container 21. Of course the water container 27 is connected with the 85 chimney 28, so that the chimney and radiator may be removed as a unit from the incubator at any time desired, and for any purpose whatsoever. The top of this water container 27 is provided with a water inlet 90 29, so that the container and radiator can be supplied with the necessary amount of water, which of course radiates heat and maintains the incubator at a proper temperature. 95

For the purpose of regulating the temperature of the incubator I provide the top thereof with a ventilating opening 30, the opening being normally closed by a damper 34 which reposes upon the top of the incubator but carried by one end of a lever 32 pivoted at a point between its ends on a suitable bracket 33, which in turn is attached to the top of the incubator. The other end of this lever 32 is bifurcated as at 35 to 105 receive a rod 36 which passes upwardly through an opening in the top of the incubator for a purpose to be hereinafter described. Arranged in end to end relation with the lever 32 is another longer lever 37, 110 the latter being pivoted as at 38 on a suitable bracket 39 also secured to the top of the

2

incubator. The adjacent ends of these levers 32 and 37 respectively overlap, so that the former is actuated by the latter when it is tilted upon its pivot in one direction. 5 Projecting from the other end of the lever 37 is an extension 40 which carries a damper 41 which normally reposes upon the chimney above referred to thereby confining the heat within the chimney when the heater is initially brought into use with a view of heating the water in the radiator and incidentally heating the incubator to the proper temperature in quick order. The rod 36 above mentioned extends upwardly through the 10 top of the incubator passes through an opening in the adjacent end of the lever 37 being threaded at its upper end to receive a nut 42 which of course reposes upon the upper surface of the lever 37. This rod 36 depends 15 from the cover into the incubator and is terminally connected with the adjacent end of a weighted lever 44, the latter being fulcrumed between its ends as at 45 upon the bifurcated extremity of a substantially L-shaped bracket arm 46 which is also secured to the underside of the cover of the incubator. Also supported on the L-shaped bracket arm 20 46 is a thermostat 47 which is riveted or otherwise secured as indicated at 48. The inner end of the free end of the lever 44 is disposed directly in the path of expansion of the thermostat so that upon overheating of the incubator the lever 44 will be rocked and through the instrumentality of the parts 25 32 and 37 the dampers 34 and 41 will be

elevated as indicated in Figure 5. This will permit the escape of heat through the opening 30 and chimney 28.

While it is believed that from the foregoing description, the nature and advantages 40 of the invention will be readily apparent, I desire to have it understood that I do not limit myself to what is herein shown and described and that such changes may be resorted to when desired as fall within the 45 scope of what is claimed.

Having thus described the invention, I claim:

The combination with an incubator including a heater having a ventilating opening and a ventilating opening in the incubator, of a thermostat arranged within the incubator, a pair of levers arranged in longitudinal alinement and pivoted intermediate their ends upon the incubator and having 50 their adjacent ends arranged in overlapping relation, a pin passing loosely through the overlapping ends of the levers, an operating lever pivoted intermediate its ends within the incubator and having one end connected with the pin and its opposite end disposed in the path of movement of the thermostat, a nut threaded upon the pin whereby to adjust the overlapping ends of the levers, and dampers carried by the opposite ends 55 of the levers for controlling the ventilating openings of the heater and incubator.

In testimony whereof I affix my signature.

MOSES E. LEWIS.
